(57) **CLAIM**

(**) Term: **14 Years**

The ornamental design for a gear case for an electro-hydraulic apparatus, as shown and described.

(21) Appl. No.: **29/165,672**

DESCRIPTION

(22) Filed: **Aug. 14, 2002**

FIG. 1 is Top plan view;

(51) LOC (7) Cl. **15-09**

FIG. 2 is Front elevational view;

(52) U.S. Cl. **D15/149**

FIG. 3 is Bottom view;

(58) Field of Search D15/148, 149; 477/139, 163, 164, 162, 155, 53

FIG. 4 is Rear elevational view;

(56) **References Cited**

FIG. 5 is Right side elevational view; and,

U.S. PATENT DOCUMENTS

FIG. 6 is Reference perspective view 2.

3,659,481 A * 5/1972 Espenschied 477/53

The left side elevational view is a mirror image of the right side elevational view.
